[57] **CLAIM**

The ornamental design for a combined bottle opener, can opener, and corkscrew brace, as shown and described.

DESCRIPTION

FIG. 1 is an isometric view of a combined bottle opener, can opener, and corkscrew brace showing my new design, wherein a broken line depiction of portions of a pair of handles for a multipurpose tool is included to illustrate the environment in which the combined bottle opener, can opener, and corkscrew brace is utilized and forms no part of the claimed design;

FIG. 2 is a right side elevational view of the combined bottle opener, can opener, and corkscrew brace shown in FIG. 1; FIG. 3 is a top plan view thereof;

FIG. 4 is a left side elevational view thereof;

FIG. 5 is a bottom plan view thereof;

FIG. 6 is a front end view thereof; and,

FIG. 7 is a rear end view thereof.
